Specification for Design.

Patented July 12, 1910.

Application filed March 7, 1910. Serial No. 547,948. Term of patent 7 years.

To all whom it may concern:

Be it known that I, HARRISON ARTHUR SILSSEE, a citizen of the United States, residing at New Bedford, in the county of Bristol and State of Massachusetts, have invented a new, original, and ornamental Design for a Glass Vessel, of which the following is a specification, reference being had to the accompanying drawing, forming part thereof.

The figure is a side-view of a glass vessel showing my design.

The four petals of a flower are represented by *a*, *a*, *a*, *a*, joined at the base; from the center of which projects a spray *b*. From the base of the flower spring deeply cut leaves *c*, *c*, *c*.

I claim—

The ornamental design for a glass vessel as shown and described.
